UNITED STATES PATENT OFFICE

106,424

DESIGN FOR A RADIO

James M. Clark, New York, N. Y.

Application January 27, 1937, Serial No. 67,302

Term of patent 3½ years

To all whom it may concern:

Be it known that I, James M. Clark, a citizen of the United States, residing at New York city, in the county of New York and State of New York, have invented a new, original, and ornamental Design for Radios, of which the following is a specification, reference being had to the accompanying drawing, forming part thereof.

Fig. 1 is a plan view of a radio, showing my new design;

Fig. 2 is an end elevational view of the same; and

Fig. 3 is a front elevational view of the same.

The rear portion of the design bears the outline shape indicated by the figures and is otherwise of conventional appearance.

I claim:

The ornamental design for a radio, as shown and described.

JAMES M. CLARK.
